PRESSURE RELEASED DEVICE

Filed April 26, 1944

UNITED STATES PATENT OFFICE

2,493,644

PRESSURE RELEASEING DEVICE

Harry N. Rider, Youngstown, Ohio, assignor, by
mesne assignments, to "Automatic" Sprinkler
Corporation of America, Youngstown, Ohio, a
corporation of Delaware

Application April 26, 1944, Serial No. 532,840

4 Claims. (Cl. 169—17)

1

This invention relates to heat actuated devices and more particularly to a sprinkler valve actuator.

The principal object of the invention is the provision of means to release air pressure from a sprinkler valve actuator the said means being adapted to be installed in an enclosure wherein pressures in excess of atmospheric are normal.

A further object of the invention is the provision of a pressure relieving device which is capable of action in an enclosure in which pressures in excess of atmospheric are normal and which device is adapted to be placed in communication with a sprinkler valve actuating device.

A still further object of the invention is the provision of a pressure releasing device adapted for positioning within a tank-like enclosure by way of a single relatively small opening in the same.

A still further object of the invention is the provision of a pressure relieving device which is efficient and dependable in operation and capable of economic manufacture.

The pressure releasing device shown and described herein has been designed to enable the positive detection of fire or conditions likely to result in fire when installed in tank-like enclosures which may or may not confine pressures in excess of or below atmospheric when used in connection with a sprinkler valve actuated device such as known in the art. For example, the pressure releasing device herein disclosed is particularly adapted for installation in solvent recovery tanks used in the manufacture of explosives, the device of the invention being located within the tank-like enclosure and serving to actuate a deluge valve of a deluge sprinkler system, the fluid delivery portions of which are also located within the solvent recovery tank. The pressure releasing device is adapted to release operating pressure normally maintained in the sprinkler valve actuating device with which it communicates and also in a portion of the device itself so that upon relieving such pressure the sprinkler valve controlled by the sprinkler valve actuator may be operated.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

2

The invention is illustrated in the accompanying drawing, wherein:

Figure 1 is a cross sectional side elevation of the pressure releasing device showing the same in normal condition.

Figure 2 is an illustration of the pressure releasing device modified in its connections for installation in a material conveying duct.

Figure 3 is a cross sectional side elevation of a tank-like enclosure showing the location of the pressure releasing device installed therein together with the fluid delivering portions of a deluge sprinkler system subject to actuation thereby.

This application for patent discloses an improvement to one of the heat actuated devices disclosed in my copending application for patent, Serial No. 462,631 on Sprinkler valve actuating device, filed October 19, 1942, which has matured into Patent 2,349,883.

By referring to the drawings and Figure 1 in particular it will be seen that the pressure releasing device consists of a tubular body member 10 having externally threaded areas 11 and 12 respectively, at its opposite ends and provided with a hexagon shaped exterior section 13 and an interiorly positioned shoulder 14 immediately beneath which there is customarily located a disk 15. The disk is positioned immediately beneath the shoulder 14 of the body member 10 by means of a ring of fusible solder. The disk 15 is held against the shoulder 14 by the fusible solder 16 in a manner forming an air tight partition across the body member 10 of the device.

Threadably engaging the threaded area 12 of the body member 10 at the bottom thereof there is a cap portion 17 which in turn is provided with an opening 18 in which a pin 19 is positioned so that the majority of the body of the pin 19 lies within the area of the cap 17 and immediately beneath the bottom of the body member 10. The pin 19 prevents the disk 15 from closing the orifice in the cap 17. The cap 17 of the pressure release device is provided with a threaded opening 20 which is adapted to receive a fitting 21 which, in Figure 1, establishes communication with a tube 22.

The pressure releasing device body 10 is mounted for operation in a T fitting 23 by means of a drilled and tapped fitting 24, which fitting 24 provides a communication channel between the interior of the T 23 and the body member 10 of the pressure releasing device so that air pressure maintained in the interior of the T 23 by way of a tube 25 in communication therewith

may be relieved upon the fusing of the fusible solder 16 and the dropping of the disk 15 in the body member 10 of the pressure release device, which action is insured by the provision of a spring 26 which is positioned between the inner end of the fitting 24 and the disk 15.

In actual practice, as may be seen by referring to Figure 3, the tube 25 communicates with a sprinkler valve actuating mechanism housing 40 in which predetermined air pressure is maintained by a suitable source. The sprinkler valve actuating mechanism, known in the art, is so formed that it will open the sprinkler valve 41 which it controls upon the loss of air pressure from the housing 40, which communicates with the tube 25 and the interior of the T 23. The loss of air pressure from the housing results from the fusing of the fusible solder 16 and the forceable displacement of the disk 15 by the spring 26 thus opening a communication channel to the atmosphere through the pressure releasing device body 10 by bringing the tube 25 into communication with the tube 22 heretofore referred to and with the tube 29 which is connected to the said tube 22 and which leads to the exterior of the enclosure.

By referring to Figure 1 of the drawings, it will be seen that the tube 22 is brazed in a fitting 27 which in turn is brazed in a fitting 28 which is brazed in the T 23. A tube 29 which leads to the exterior of the enclosure is brazed in the opposite end of the fitting 28. Thus, a leak proof communication channel is effected between the tube 22 and the tube 29. The tube 29 is located within the tube 25 and extends to the atmosphere outside of the tank or other enclosure 42 in which the device may be located so that air pressure relieved by the device may be vented through the tube 29 to the atmosphere. As this action has been carefully set forth in my heretofore referred to co-pending patent application on sprinkler valve actuating device in which disclosure a different mechanism is employed in place of the pressure releasing device herein disclosed, a further description of the mode of operation is not included herein.

By referring now to Figure 2 of the drawings, it will be seen that a pressure releasing device 30 modified somewhat from that illustrated in Figure 1 of the drawings and heretofore described, has been positioned in a material conveying duct 31 wherein pressures in excess of or below atmospheric are normal.

The pressure releasing device 30 takes the form of a tubular body having a plurality of heat absorbing fins 32 positioned thereabout which heat absorbing fins speed up the action of the device upon subjection to heat due to the ability of the finned body member 30 to absorb heat more rapidly. Like the device illustrated in Figure 1, the pressure releasing device 30 is mounted by means of a fitting 33 which, in Figure 2, is positioned in a reducer 34 which in turn is affixed to a tube 35 which extends through the duct wall 31 in an air tight manner and communicates with the sprinkler valve actuating device mechanism housing in which actuating air pressure is maintained as heretofore described in connection with the tube 25 in Figure 1. In order that air in the tube 35 may be vented upon operation of the pressure releasing device 30, a cap 36 similar to the cap 17 in Figure 1 is provided with a drilled and tapped opening in which a fitting 37 is positioned so as to establish communication with the tube 38. The opposite end of the tube 38 ex-

tends through the duct wall 31 where it is positioned in an air tight manner and communicates with the atmosphere at a point 39.

It will thus be seen that the pressure releasing device disclosed herein is capable of actuating a sprinkler valve actuating mechanism by relieving the pressure therein to the atmosphere upon being subjected to heat and that by its construction it is particularly adapted for positioning within tank-like enclosures in which pressures in excess of or below atmospheric are common.

Having thus described my invention, what I claim is:

1. A pressure releasing device for installation in a tank like enclosure whereby pressures other than those in the enclosure may be controlled by the temperature within the enclosure, said device including a T-shaped hollow body member and including a pair of tubular members in communication therewith, said tubular members extending out of said tank-like enclosure, means to separate the T-shaped body member into two chambers and heat responsive pressure releasing means controlling the separating means, one of the tubular members establishing communication with the bottom of the T-shaped body member on one side of the separating means and the other of the tubular members establishing communication with the T-shaped body member above the separating means, the tubular members and the pressure releasing device closed with respect to the interior of the said tank-like enclosure.

2. A pressure releasing device for installation in a tank like enclosure whereby pressures other than those in the enclosure may be controlled by the temperature within the enclosure, said device including a hollow body member having a tubular projection extending therefrom, means in the tubular projection separating a portion thereof from the remainder of the hollow body member, said separating means comprising a heat responsive pressure releasing element, a tubular member in communication with the outward end of the said projection and the chamber on one side of the said separating means and extending through the said hollow body member and separated therefrom, and a secondary tubular member establishing communication with the said hollow body member on the other side of the said separating means and enclosing the first mentioned tubular member, said tubular members extending to a location outside the said tank-like enclosure, said hollow body member and tubular members closed with respect to the said tank-like enclosure.

3. A pressure releasing device for installation in a tank like enclosure whereby pressures other than those in the enclosure may be controlled by the temperature within the enclosure, said device including a hollow body member having a removably affixed tubular body member extending therefrom, a fusible element in the said tubular body member separating the outermost portion thereof from the hollow body member, a tubular member in communication with the outward end of the said tubular body member and the chamber on one side of the said fusible element and extending through the said hollow body member and separated therefrom, and a secondary tubular member establishing communication with the said hollow body member on the other side of the said separating means and enclosing the first mentioned tubular member, said tubular members extending to a location outside the said

tank-like enclosure, said hollow body member and tubular members closed with respect to the said tank-like enclosure.

4. A pressure releasing device for installation in a tank like enclosure whereby pressures other than those in the enclosure may be controlled by the temperature within the enclosure, said device including a hollow body member having a removably affixed tubular body member extending therefrom and in communication therewith, a 10 fusible element in the said tubular body member separating the outermost portion thereof from the remainder thereof, a tubular member in communication with the outermost end of the said tubular body member, and a secondary tubular member establishing communication with the said hollow body member on the other side of the said separating means, said tubular members extending to a location outside the said tank-like enclosure, said hollow body member and tubular members closed with respect to the said tank-like enclosure.
